Primary Examiner — Catherine R Oliver-Garcia(74) *Attorney, Agent, or Firm* — Bold IP, PLLC;
Christopher Mayle(57) **CLAIM**

The ornamental design for a fishing lure, as shown and described.

DESCRIPTION

FIG. 1 is a front perspective view of a first embodiment of the fishing lure in accordance with the present invention; FIG. 2 is a front side view thereof; FIG. 3 is a rear side view thereof; FIG. 4 is a left view thereof; FIG. 5 is a right view thereof; FIG. 6 is a top view thereof; and, FIG. 7 is a bottom view thereof. The broken lines in FIGS. 1-7 represent environmental elements, which form no part of the claimed design.

1 Claim, 5 Drawing Sheets(56)
